UNITED STATES PATENT OFFICE.

JOHN A. MILLER, OF HOMEWOOD, ILLINOIS.

PLEASURE RAILWAY CAR.

Application filed February 24, 1927. Serial No. 170,518.

My invention relates to pleasure railway cars and covers particularly supporting handle and guard structure and arrangement for facilitating and expediting loading and unloading of the cars, for providing convenient and secure grip support for guiding passengers to and from the car seats and for enabling them to retain the seats while the car is traveling, and for guiding against and protecting the passengers from falling out at the sides of the car when the car is rounding curves.

My improved structure and arrangement is permanent and rigid and eliminates gates, chains, bars, etc., which require locking and unlocking operations and which may become unlocked while the car is traveling.

My invention also contemplates improved supporting structure and arrangement for a canopy or shelter top for the cars which supporting structure provides additional gripping and holding supports for the passengers particularly when entering or leaving a car.

25 On the drawings:

Figure 1 is a side elevational view, and

Fig. 2 is a sectional view on plane 2—2 of Fig. 1.

The body of the car shown comprises side beams or walls 10 and 11 connected together by cross beams 12 and the front and end walls 13 and 14. The car is mounted on suitable wheel structures 15 over which extend the running boards 16 and 17. The cross beams 12 support the floor 18 at the front of the body. Each seat structure comprises side walls 19 and 20, a back or rear wall 21, and a seat board 22. Cushions 23 may be provided on the seat boards and up-holstering 24 on the back walls, the height of the cushioned seat being such that the passengers may comfortably place their feet on the floor 18. The stepping or running boards 16 and 17 lead to the aisles 25 between the seats, the floor 18 being below the top surfaces of the running boards, thus bringing the seats down low so that the center of gravity of the car is correspondingly low to insure safety.

50 Heretofore, gates, chains, bars, and other detachable or movable means have been provided for preventing the passengers from

falling laterally out of the car at the ends of the aisles and tending to keep the passengers seated on the seats. All such arrangements, however, require unlocking or movement to permit the passengers to enter a car and then locking in operative position, all of which requires time and detracts from the capacity and efficiency of a pleasure railway structure. In accordance with my present invention I eliminate all these movable or adjustable locking devices or supports and substitute permanent and rigid structures which will give adequate grip 55 and holding accommodations to the passengers, which will facilitate and expedite loading and unloading, and which will prevent passengers from falling out of the car when the car takes sudden dips or travels around 60 curves. To carry out my invention, I provide handle and guard structures 26 and 26' opposite the ends of each aisle and spaced away from the seat ends to leave entrance and exit passageways 27 and 27' respectively of sufficient width to permit passengers to easily and readily move longitudinally 65 along the running boards to and from the transverse aisles between the seats. The handle bar and guard structures will then 70 prevent the passengers from toppling or falling out of the car from the ends of the aisles. In the particular arrangement shown the upper end sections 28 and 28' of the back of each seat structure are extended laterally beyond the seat side and form supports for the handle and guard structure 26 and 26' which as shown may be bent from metal bar or pipe and comprising the upper 75 horizontally extending section *a* and the diagonally extending lower or brace section *b*, the ends of the sections being secured to a base plate or frame 29 bolted or secured to the extensions 28, 28'. The structures *a* *b* extend the full width of the transverse aisles 80 and may extend a distance beyond, and between them and the seat sides are found the longitudinal passageways 27, 27' above referred to as leading to the transverse aisles. Passengers enter at one side of a car and leave at the other where the car travels between loading and unloading platforms and the passengers can readily move along the running boards in the passageways 27 and 85 90 95 100

27' to or from the aisles 25 and can support and guide themselves by the handle structures 26 and also by handle bar structures 30 extending longitudinally in front of each 5 seat from the back of the preceding seat. These handle bars 30 may extend a sufficient distance rearwardly to guard against passengers being thrown upwardly out of the car when the car takes sudden dips, and the 10 ends 30' of the handle bars are gradually rounded or slanted off so as not to interfere with the entrance or leaving of passengers to and from the seats during loading and unloading of the cars. The handle bars 30 15 make it difficult for a passenger to bring himself to the erect position when the car is traveling and even should he do so the guard structures 26, 26' at the ends of the aisles will give him support and prevent 20 his falling from the car at the ends of the aisles. As these handle bars and guard structures are rigid and permanently secured, loading and unloading of a car is facilitated and expedited and considerable time saved 25 and there is no danger of locks or movable or adjustable securing means becoming unfastened as was the case where movable gates, chains, bars or the like were used.

I also provide a canopy or shelter top 32 30 supported on side posts 31 and front and rear posts 36 and 37 respectively. The side and front posts may extend from supporting bases 33 fastened to the running board of the car and the side posts may be firmly 35 secured to the extensions 28 and 28' by means of cleats 34. The rear post may be supported in a bracket 38 secured to the back of the rear seat. The front post 36 may be secured to the dash structure *d* and as shown, it 40 extends through the top board 39, between which top board and the canopy extends the windshield 35. This windshield may be a glazed frame or may be a flexible structure of transparent material such as celluloid.

45 The rear seat does not have extensions 28 and 28', and at the front of the car the extensions 28 and 28' are at the ends of the dash structure and support the guard structures 26.

50 The side posts extend upwardly from the outer edge of the running boards so that the canopy may overhang the ends of the seat a considerable distance so as to afford ample shelter particularly against rain 55 without need of side curtains. The posts will assist passengers in entering or leaving a car by affording secure holds. The canopy is sufficiently low to prevent passengers from standing upright and it will prevent 60 passengers from being hurled or jumping vertically from the car.

Having described my invention, I claim as follows:—

65 1. In a pleasure railway car, the combination of a body having running boards along

its sides, transverse seats on said body, and combined handle and guard structures supported over said running boards to extend across the spaces between the seats and at a distance away from the seat ends to provide passageways from the running boards to the spaces between the seats. 70

2. In a pleasure railway car, the combination of a support body, cross seats thereon, running boards along the sides of the body, 75 and stationary supporting brackets extending from the backs of the seats across the spaces between the seats and a sufficient distance outside of the seat ends to provide passageway from the running board to the 80 spaces between the seats.

3. In a pleasure railway car, the combination of a car body, cross seats on said body, running boards at the sides of said body adjacent to the seat ends, each seat 85 comprising end walls and a rear wall, the rear walls of each seat being extended at its ends to form supporting extensions, and handle and guard structures secured to said supporting extensions and extending across 90 the spaces between the seats. 95

4. In a pleasure railway car, the combination of a car body, a row of transversely extending seats thereon, and guard structures supported at the ends of each seat and extending rearwardly thereof to shut off direct passage to and from the spaces between the seats, said supporting structures being spaced laterally away from the seat ends to provide passageways to the spaces between 100 the seats.

5. In a pleasure railway vehicle, the combination of a body part having running boards extending along the sides thereof, seats extending transversely of said body between said running boards, supports extending laterally from the ends of said seats, grip guard structures rigidly secured to and extending rearwardly from said supports to overhang said running boards outside of the passageways between the seats and spaced from the ends of the seats to leave passageway for the passengers entering or leaving the seats. 105 110

6. In a pleasure railway vehicle, the combination of a body part having running boards along the sides thereof, seats extending transversely from said body parts between said running boards, supporting extensions on the ends of said seats overhanging said running boards, guard and hand rails rigidly secured to said supporting extensions and extending rearwardly past the ends of the spaces between the seats and spaced from the ends of the seats to leave 115 passageway for passengers entering or leaving the seats, posts secured to said supporting extensions and being spaced away from the ends of the seats, a shelter top carried by said posts, said posts affording additional 120 125 130

hold and support for the passengers of the vehicle.

7. In a pleasure railway car, the combination of a body part, seats extending transversely on said body part, and guard rail structures rigidly secured on said body part opposite the ends of the spaces between said

seats but spaced away from the seat ends to leave passageways for passengers entering or leaving the car.

10

In witness whereof, I hereunto subscribe my name this 17th day of February, 1927.

JOHN A. MILLER.
